COMB

Harold F. Shaw, Leominster, Mass.

Application August 10, 1946, Serial No. 689,742

13 Claims. (Cl. 132—22)

1

This invention relates to combs of the type used by women for holding the hair in place after the coiffure is suitably arranged. The object is to provide a hair positioning or retaining device of this nature having teeth which, after they have been inserted in the hair, may be brought closer together more firmly to grip the hair and which will be locked in this position, the comb then becoming a part of the hair arrangement, either inconspicuous or conspicuous and ornamental as the case may be. The comb will then not fall out or easily become displaced and the coiffure will not become disarranged.

My invention will be well understood by reference to the following description taken in connection with the accompanying drawings, wherein I have shown various constructions illustrative of the invention and wherein:

Fig. 1 is a plan of a comb with its parts in the position which they occupy when in use in the hair;

Fig. 2 is a similar view showing the parts in the open position which they will occupy prior to the insertion of the teeth in the hair;

Fig. 3 is a rear view of Fig. 2, the teeth being broken away;

Fig. 4 is a section on the line 4—4 of Fig. 3;

Fig. 5 is a view of the upper portion of a comb of modified construction, the parts being in the open position;

Fig. 6 is a section on the line 6—6 of Fig. 5;

Fig. 7 is a view similar to Fig. 5 showing a different modification; the teeth of the comb are also of a different form;

Fig. 8 is a section on the line 8—8 of Fig. 7;

Fig. 9 is a view similar to Figs. 5 and 7 showing a different modification;

Fig. 10 is a fragmentary view of the central portion of Fig. 9 showing the parts in positions into which they move when the comb is closed or locked;

Fig. 11 is a view of the upper portion of another modified form of comb in the open position and viewed from the rear;

Fig. 12 is a fragmentary section on the line 12—12 of Fig. 11; and

Fig. 13 is a fragmentary view similar to Fig. 12 showing the parts in the closed or locked position.

Usually combs of the kind shown are curved in a plane perpendicular to the paper in the drawing, but I have not attempted to illustrate this with accuracy in the drawing as it would complicate the drawing and not contribute to an understanding of the invention. In the following description I shall speak of the devices illustrated as if flat in the plane of the paper.

Referring now to Figs. 1 to 4, inclusive, the comb there shown comprises a unitary body corresponding in general in its form to a complete comb of the conventional kind and which may conveniently be molded from suitable plastic material such as paryxvin and comprises a back

2

20 from which projects a row of teeth 22. Herein the teeth 22 are shown with projections 24 staggered in adjacent teeth, these illustrating by way of example teeth having a formation intended to resist their withdrawal from the hair, a function which they more efficiently perform in a construction embodying the present invention, as will hereafter appear. The back 20 is resiliently flexible and may be flexed in the plane of the paper and normally when not constrained would occupy such a position as seen in Figs. 2 and 3 wherein it extends substantially straight.

In the modification of Figs. 1 to 4, a bar 26 is associated with the back 20 of the comb, herein being mounted thereon a central pivot 28. It may be made of like plastic material and in the example shown is of simple form and appears, when the comb is in the position of use shown in Fig. 1, much like an ordinary back portion of the usual unornamented side comb or the like. While this bar 26 may flex somewhat in practice, it is relatively heavy and it will be convenient here to consider it as rigid in the plane of the paper although it may be resiliently flexible transversely to that plane. Herein the bar has a generally curved form and has overhanging shoulders 30 (see Figs. 3 and 4) preferably with recurved hook-like ends as seen in the latter figure which are offset downwardly from the pivot 28 and adapted 30 in the closed position of Fig. 1 to engage the end portions of the back 20 which may be provided with suitable seats 32 to receive the same. The pivot 28 and the points of engagement of the shoulders 30 lie on a curve of greater curvature than the back 20 when the lever is in the position shown in Fig. 1. The comb with the parts in the position in Fig. 2 is inserted in the hair. The back 20 and the bar 26 remain exposed at the outside of the hair. The fingers may then swing the bar 26 counterclockwise, viewing Fig. 2, and the shoulder 30 at the left will come to rest on seat 32 while that at the right is snapped over the seat 32 at the right-hand end of the back 20. By this action the back of the comb is fixed to correspond with the curve of the three engaging points and therefore the teeth 22 are thrown into their converging positions, illustrated in Fig. 1, locking them to the hair. Thus if we assume the back 20 to be perfectly horizontal in Fig. 2, the teeth 22 might be considered as perpendicular thereto and parallel. Then if the back is bent to the arc of a circle, the teeth assume the position of radii converging toward the center. This may be considered a schematic description of the principle of action.

When it is desired to withdraw the comb, one end of the bar 26 may be stressed slightly to be sprung aside to disengage its shoulder 30 from seat 32 and permit the bar to swing to the position of Figs. 2 and 3. The body of the comb then springs back to its normal unstrained position of Fig. 2. If the back 20 of the comb is normally substantially straight, it is flexed in use to a

curve. If initially curved, it is flexed to a sharper curve. The straight position may be considered as a limiting case. It would also be possible to have an initial negative curvature, that is, the back might be concaved upwardly, and this curvature would then be flattened.

If we consider the parts in the open position of Fig. 2, it will be plain that the distance between the two terminal engaging seats 32 of the back 20 is substantially the same as the distance between the shoulders 30 measured along the bar on the curve through the pivot 28. The distance between the shoulders 30 on the bar 26, measured in a straight line, is less, the chord being shorter than the arc. When the device is closed to the position of Fig. 1, the seats 32 on the back are pressed nearer together to correspond to the straight line spacing of the shoulders 30 with resultant flexure of the back 20, causing the ends of the teeth to move closer together.

The description of the principle of action which has just been given is particularly useful in considering the construction of Fig. 5. Herein the bar 126 is associated with the back 20 by being pivoted thereto at one end only and at the other end it is recurved to form a hook 130 which embraces the right-hand end of the back when closed, coming to rest against a shoulder 132. The parts are so proportioned that the hook can be engaged only if the back 20 is sprung or flexed to increase its curvature and throw the teeth to more converging positions.

In the modification of Figs. 7 and 8, the bar 226 is associated with the back by being pivoted thereto centrally at the point 228 and at the left at point 229 while the right-hand free end carries a hook-like latch 230 which is adapted to be engaged over the upper edge of the back 20 of the comb at its right-hand end. The points defined by the two pivots 228 and 229 and the latch 230 define a curve more abrupt than the normal curvature of the back 20, and when the latch is engaged the back is flexed to throw the teeth into more convergent positions.

In this construction the right-hand end of the comb back and of the bar 226 may be pressed apart corresponding to a swinging movement of the bar clockwise, part of the back between the points 228 and 229 flexing to accommodate it to such movement, to spread the ends of the teeth before they are inserted in the hair. They will resiliently regain their normal position when the bar is released and when the bar is latched will move beyond the same to more convergent positions as in the other constructions.

In Fig. 7 and likewise in Figs. 9 and 11 the teeth 222 are different from the teeth illustrated in Figs. 1, 2, 3 and 5, being substantially of the form shown in the patent to Sawyer No. 1,684,362, the teeth having elongated openings throughout the major portion of their length defining resiliently bowed sides which in a construction as described will be pressed together and mutually compress one another when the comb is brought to the closed position.

Referring to Fig. 9, the comb body, which is generally like those previously described, carries on its back a curved bar 326 connected to the back 20 adjacent the ends of the latter by pivot pins 328, the bar 326 and the back 20 being related one to another in substantially the manner of an arc and its chord. A finger lever 336 is associated with these parts by being pivoted to the back at point 338 while a link 340 pivoted to the lever at point 342 extends to pivot point 344 on the 75

bar 326. If the lever is swung counterclockwise from the position of Fig. 9, the central portion of the back 20 will be drawn up into the concave of the bar 326, being bent to the form of the arc, and the teeth will be caused to converge.

The link 340 is desirably somewhat longer than the distance between the points 338 and 344 and may move slightly beyond center to the position shown in Fig. 10 and will be self-maintaining in that position. The mechanism is one form of toggle joint. In this instance the mere manipulation of the lever in itself tends to move the teeth to the desired convergent positions and holds them there until released by a suitable reverse manipulation.

In Fig. 9, I have indicated by dotted lines 346 the outline of an ornamental piece which might be mounted on the bar 326 and which would effectually conceal the operating mechanism when 20 the comb was worn.

In the modification shown in Fig. 11, a bar 426 of arc-shaped form and of generally channel-shaped section, as seen in Figs. 12 and 13, is associated with the back 20 of the comb by being secured to the ends of the back 20 at points 428. In the open position of Figs. 11 and 12, the back 20 is related to the bar 426 in the manner of a chord to its arc. The central portion of the bar 20 may be drawn up into the channel and flexed to the curvature thereof to cause the teeth of the comb to converge. To retain it, a locking member 448 is provided the upper end of which is hinged to the back bar at the central portion of the latter, and which has a hook-shaped lower end 450 which 35 may be swung in under the lower edge of the back 20 to the position shown in Fig. 13, the resiliency of the flexed back holding the latch engaged. As in the other cases, the teeth of the comb are 40 pressed in the hair with the parts in the position of Figs. 11 and 12. The back is then flexed and locked in that position by the engagement of the hook 450 with the lower edge of the back.

I have referred to the part 26, 126, and so on, as a bar, but it obviously might take various forms, ornamental if desired or of a considerable area, provided engaging parts are present properly related to perform the functions described. Ornamental extensions could be formed separately and mounted on such a bar, as above suggested in connection with Fig. 9, and wide varieties of ornamental forms could be provided by assembling different tops with a simple bar of the type, for instance, that shown in Figs. 1, 2 and 3, which then would not only serve as a latch 50 for securing the teeth in their locked or convergent position but provide a support for the ornamental projecting portion of the comb. Thus back combs frequently have extended projecting portions of an ornamental character and their weight and size permit them to be relatively easily displaced. When constructed in accordance with the invention they are firmly secured in position until it is desired voluntarily to withdraw them.

In a back comb such as has just been referred to, the ornamental function is perhaps more important than the hair-retaining function. It is in effect a head ornament mounted to the hair by means of comb teeth. Similarly a bow of ribbon, a flower or the like may be mounted on a comb body to be used as an ornament. The constructions here described are most effective for such uses and reference to them as hair-retaining devices is not to be understood as excluding their adaptation to such purposes.

I am aware that the invention may be em-

bodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A comb comprising a back and teeth formed as an integral unit of resilient material and a manipulable locking device associated with the back to be accessible for manipulation when the teeth have entered the hair and operating on portions of the unit to alter their relative position with resultant resilient deformation of the unit when brought to locked position serving to hold the unit in such deformed position with the points of the teeth more closely approximated than when the unit is in its normal unstressed state.

2. A comb of the class described comprising a flexible back having projecting teeth, a bar co-operating with the back to engage the same at three spaced points along the bar, the engagement being releasable at at least one of said points, the points defining a curve of greater curvature than the normal contour of the back, whereby when engagement is effected at all the points the teeth are forced into and secured in a converging position.

3. A comb of the class described comprising a flexible back having projecting teeth, a bar pivoted to the back between the ends thereof and having adjacent its ends catches for releasably engaging the comb adjacent its ends, the said catches and pivot defining a curve of greater curvature than the normal contour of the back, whereby when engagement is effected at all the points the teeth are forced into and secured in a converging position.

4. A comb of the class described comprising a flexible back having projecting teeth, a bar pivotally connected to the back at points respectively between its ends and adjacent one end and having adjacent the other end a catch for releasably engaging the back, the said catch and points defining a curve of greater curvature than the normal contour of the back, whereby when engagement is effected at all the points the teeth are forced into and secured in a converging position.

5. A comb of the class described comprising a flexible back having projecting teeth, a bar pivotally connected to the back adjacent one end thereof and having a catch adjacent its other end for engaging the comb adjacent its other end, the distance between the pivot and catch being less than the normal distance along the unflexed back between the pivot and the point of engagement of the catch, whereby when the two ends of the back are both engaged with the bar the teeth are forced into and secured in a converging position.

6. A comb of the kind described comprising a flexible back having projecting teeth, a bar associated with the back having a different curvature than the back in the normal form of the latter and means for locking the back to said bar to bring and maintain the former to flexed position with the teeth in more converging positions.

7. A comb of the kind described comprising a

bendable back having projecting teeth, a bar associated with the back having a different curvature than the back in the normal form of the latter and means for bending the back to the curve of the bar and holding it thereto to bring the teeth to and maintain them in more converging positions.

8. A comb of the kind described comprising a flexible back having projecting teeth, a bar pivoted to the back of the comb having means for engaging the ends of the comb which means are closer together than the normal spacing of said ends, whereby when the bar is swung on its pivot to engage said means with both ends of the comb the latter is flexed and the teeth forced into and secured in converging positions.

9. A comb of the class described comprising a flexible back having teeth projecting therefrom, a bar having a greater curvature than the back connected to the ends thereof, and a device carried by one of the parts for latching the central portion of the back in flexed position to the central portion of the bar with the teeth forced into and secured in converging positions.

10. A comb of the class described comprising a flexible back having teeth projecting therefrom, a bar having a greater curvature than the back connected to the ends thereof, and a device carried by one of the parts for drawing and latching the central portion of the back into the concave defined by the bar with the teeth forced into and secured in converging positions.

11. A comb of the class described comprising a flexible back having teeth projecting therefrom, a bar having a greater curvature than the back connected to the ends thereof, and a lever device mounted between the central portions of the bar and back for drawing the same together said device moving to a self-maintaining position when they are so drawn together with the teeth forced into and secured in converging positions.

12. A comb of the class described comprising a flexible back having teeth projecting therefrom, a bar movably mounted on the back of a curvature different from the back and having provision for releasably engaging the back to hold the same flexed to a curvature at least more nearly approximating that of the bar with the ends of the teeth closer together than when the back is in its normal unstressed position.

13. A comb of the kind described comprising a unitary flexible back having integral teeth projecting therefrom and a device associated with the back manipulable into engagement with a portion of the back for locking the back in a flexed form of increased curvature with the teeth forced into positions of increased convergence.
